Primary Examiner — Michelle E. Wilson(74) *Attorney, Agent, or Firm* — Banner & Witcoff, Ltd.(57) **CLAIM**

The ornamental design for a sprayer for dishwasher, as shown and described.

DESCRIPTION

FIG. 1 is a front perspective view of a sprayer for a dishwasher showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken line showing of the various elements of the sprayer for a dishwasher represents unclaimed subject matter and forms no part of the claimed design. The broken line showing of the remainder of the sprayer for a dishwasher represents unclaimed subject matter and forms no part of the claimed design. The contrast in shading represents a contrast in appearance only and does not represent any particular color, texture, or finish.
